[57] CLAIM

The ornamental design for a jewelry display stand, as shown and described.

DESCRIPTION

FIG. 1 is a perspective view of a jewelry display stand showing our new design;

FIG. 2 is a front elevational view thereof;

FIG. 3 is a top plan view thereof;

FIG. 4 is a left side elevational view thereof;

FIG. 5 is a rear elevational view, the right side being identical thereto;

FIG. 6 is a bottom plan view thereof;

FIG. 7 is a perspective view of a second embodiment of the jewelry display stand shown in FIG. 1;

FIG. 8 is a front elevational view thereof;

FIG. 9 is a top plan view thereof;

FIG. 10 is a left side elevational view thereof;

FIG. 11 is a rear elevational view the right side being identical thereof; and,

FIG. 12 is a bottom plan view thereof.
